6 Claims. (Cl. 103—103)

This invention relates to centrifugal pumps and more particularly to a highly efficient and reliable pump to be utilized in critical installations such as aircraft.

In relationship to aircraft engines and systems, centrifugal pumps are used in many ways. These uses include oil pumps for lubricating systems, pumps for hydraulic control systems and water pumps for water injection systems. For such aircraft utilization, it is desirable to reduce to a minimum the possibility of failure in flight. At the same time, it is desirable to have the pumps as efficient as possible so that they can accomplish the designed requirements while requiring a minimum of power to operate them.

It is an object of the present invention to provide a new and improved centrifugal pump.

Another object is to provide a centrifugal pump which will have both a high efficiency and a low probability of failure.

A further object is to provide a centrifugal pump having stiffeners on one edge of the impeller blade to reduce vibration and the possibility of fatigue failure.

A still further object is to provide a more efficient impeller housing having an annulus with a semi-circular cross section equal to the throat diameter of the diffuser.

Still another object of the present invention is to provide a more efficient centrifugal pump impeller by having blades which are rounded off on the leading side to a thin tip.

An additional object of the present invention is to provide a more efficient centrifugal pump having a double cone diffuser wherein the first cone has the optimum diffuser angle and the second cone has a steeper cone angle slightly greater than the optimum.

Yet another object of the present invention is to provide a centrifugal pump having a short spiral section machined into the casing ahead of the diffuser throat for improved efficiency.

A further object of the present invention is to provide an improved dynamic seal between the drive shaft and the housing of a centrifugal pump.

A still further object is to provide a drainage system to prevent fluid from leaking from the pump along the drive shaft when the pump is either stopped or operating at a low rotational velocity.

Another object of the present invention is to provide a removable diffuser for a centrifugal pump.

Still another object is to provide a centrifugal pump diffuser having a throat portion composed of a different material than that of the diffuser body.

Further objects and advantages will become apparent from the following detailed description taken in connection with the accompanying drawings.

In the drawings:

FIGURE 1 is a sectional view taken along a vertical plane through the center line of an embodiment of the present invention;

FIGURE 2 is a sectional view taken along the line 2—2 of FIGURE 1;

FIGURE 3 is a sectional view taken along the line 3—3 of FIGURE 1.

While this invention is susceptible of embodiments in many different forms, there is shown in the drawings and

2

will herein be described in detail, an embodiment of the invention with the understanding that the present disclosure is to be considered as an exemplification of the principles of the invention and is not intended to limit the invention to the embodiment illustrated. The scope of the invention will be pointed out in the appended claims.

Referring first to FIGURE 1, a centrifugal pump housing comprising a cover member 10, a base member 11, and a sealing member 12 is secured to a supporting member 13. A bolt 14 is one of a set of bolts securing the housing cover member 10 to the support member 13. An impeller drive shaft 15 is rotatably mounted in the support member 13 by a bearing sleeve 16. The housing base member 11 has an O ring 17 retained in a groove 18 to prevent fluid leakage between the housing cover member 10 and the base member 11. The sealing member 12 abuts the base member 11 and has an O ring 19 secured in a groove 20 to prevent fluid leakage between it and the housing cover member 10.

An impeller hub 21 is secured to one end of the shaft 15 by a bolt 22. A set of eight impeller blades is secured to the hub 21. An impeller blade 23 and an impeller blade 24 of the set of impeller blades are shown in FIGURE 1. The set of impeller blades 23 through 29b are shown in FIGURE 2. Each blade has its leading side rounded off on a large radius to produce a thin blade tip.

A rigid stiffener is secured to the trailing edge of each blade. In FIGURE 1, a stiffener 30 is shown secured to the impeller blade 23 and a stiffener 31 is shown secured to the impeller blade 24. The remaining six stiffeners on the other six blades are not shown in the drawings. As the blades are rotated with the hub 21, the stiffeners rotate in the recess 32. A semi-circular annulus 33 is formed in the housing cover member 10 surrounding the tips of the impeller blades.

An intake duct 34 provides a passage through which fluid is drawn to the impeller blades. A slinger member 35 is mounted on shaft 15 to rotate therewith. An O ring 36 is retained in a slot 37 between the shaft 15 and the slinger member 35 to prevent the leakage of fluid along the shaft 15. A disc 38 is secured on the shaft 15 adjoining the slinger member 35. A retaining ring 39 is mounted on the shaft 15 between the disc 38 and a shoulder 40 of the drive shaft 15.

Referring now to FIGURE 2, a diffuser 41 is mounted in a bore 42 in the housing cover member 10. A locking bolt 43 is threaded into an aperture 44 in the housing 10 to secure the diffuser 41. A diffuser throat member 45 is mounted in a recess 46 of the diffuser 41.

The annulus 33 is positioned at a constant radius from the center of the hub 21 except for an annulus section 47 ahead of a diffuser throat 48. As shown in FIGURE 2 this section 47 of the annulus 33 departs from a constant radius in a short logarithmic spiral to connect with the diffuser throat 48 formed in diffuser throat member 45.

The diffuser throat 48 is joined to a first cone portion 49 which has an optimum cone angle. The first cone portion 49 is joined to a second cone portion 50 which has a steeper cone angle.

Referring again to FIGURE 1, a set of leakage ports are provided in the housing base member 11. A cavity 52 exists between the sealing member 12 and the supporting member 13. The cavity 52 is vented by a set of drain holes. One of these drain holes 53 is shown in FIGURE 1.

FIGURE 3 shows a set of vanes 54 forming a part of the slinger member 35.

The fluid to be pumped such as oil, hydraulic fluid or water is drawn through the duct 34 to the impeller blades. The impeller blades are driven from a suitable power

source (not shown) through the drive shaft 15 and the hub 21. The centrifugal force imparted to the fluid by the rotation of the impeller blades forces it out into the semi-circular annulus 33 and into the diffuser 41. The diffuser converts the kinetic energy imparted to the fluid by the rotation of the impeller blades into fluid pressure.

The stiffeners such as 30 and 31 reduce blade vibrations and thereby reduce the possibility of fatigue failure. Since they run in the recess 32 they do not affect the operation of the impeller blades. The use of individual stiffeners instead of a complete flange or shroud is an important advantage in that the pressure at the shaft seal is much less than the maximum pressure that is present in the annulus 33.

The semi-circular cross section annulus 33 reduces the wetted perimeter of the annulus over the usual rectangular annulus employed in normal centrifugal pumps. With a diameter equal to the throat diameter of the diffuser 41 and the diffuser throat 48 relatively free of discontinuities, the best diffuser inlet conditions are provided. Thus the semi-circular annulus 33 increases the pressure recovery in the diffuser 41. Both these effects increase the pump efficiency.

The rounding off of the leading sides of the impeller blades to as thin a tip as possible with a large radius minimizes interferences to flow as the blade tips rotate past the diffuser inlet.

The first cone portion 49 of the diffuser 41 is designed to have an optimum diffuser angle. Since it would be impractical in most aircraft installations to make the diffuser sufficiently long for the optimum cone to reach the diameter of a discharge pipe, the second cone portion 50 has a slightly steeper cone angle than the optimum. Thus the double cone diffuses the throat velocity down to discharge pipe velocity with no abrupt discontinuities in the flow path in a shorter length than would be possible if the optimum angle cone were carried out far enough to reach the diameter of a discharge pipe. The reduced length of the diffuser reduces the skin friction which partially off-sets the diffuser friction in the second cone 50.

The short logarithmic spiral section 47 machined into the casing ahead of the diffuser throat 48, provides a path for the fluid leaving the blades which allows it to flow to the diffuser throat without forcing it away from the path which it naturally tends to follow.

Referring again to FIGURES 1 and 3, slinger member 35 provides a dynamic shaft seal. Inlet pressure is exerted against the right hand face of the slinger member 35 at the outer diameter of the shaft. The side of the housing base member 11 facing the slinger member 35 is smooth and therefore imparts relatively little pressure to the fluid. Therefore the fluid at the outer diameter of slinger member 35 is at a pressure only slightly greater than inlet pressure. The vanes 54 on the left hand side of the slinger 35 can impart a considerable pressure to fluid trapped in them. Therefore, fluid will travel down the left side of the slinger only far enough to produce a pressure at the slinger member outer diameter equal to inlet pressure plus the pressure increase on the right hand face of the slinger member 35. The leakage ports 51 provide paths for fluid to flow back to the impeller blades.

If fluid is fed to the pump while it is standing still or rotating at low speed it will pass by the dynamic seal and continue along the shaft 15. The clearance between the sealing member 12 and the slinger member 35 is small. Fluid passing through the clearance must therefore do it at a slow rate compared to the rate at which the cavity 52 between sealing member 12 and support member 13 and drain holes such as 53 can vent such leakage overboard. Thus the need for any mechanical seal between the pump housing and the drive shaft 15 is eliminated. The disc 38 deflects towards the drain

holes any fluid spraying out through the clearance between the sealing member 12 and slinger member 35 into cavity 52.

Since the diffuser is a separate piece, it is possible to quickly replace it if replacement should become necessary. In addition this permits a flexibility in changing pump impellers while at the same time maintaining a proper tangential relationship between the impeller blades and the diffuser throat 48. Also a more corrosion resistant material may be utilized for the diffuser than would be desirable for the construction of the entire housing.

Since the throat insert 45 is a separate piece, it may be made of a material such as ceramic or tungsten carbide without having to make the entire diffuser out of such a material. It has been found that the diffuser throat is subject to much more erosion than any other portion of a centrifugal pump.

We claim:

1. In a centrifugal pump, the combination of an impeller comprising a hub and a set of impeller blades mounted on said hub, an impeller housing surrounding said impeller, an annulus having a semi-circular cross section in said impeller housing surrounding said impeller blades, a cone diffuser passage in said housing, and a logarithmic spiral section in said annulus and extending over less than a 90° arc of said annulus to connect said annulus to said diffuser passage.
2. In a centrifugal pump, the combination of an impeller comprising a hub and a set of impeller blades mounted on said hub, an impeller housing surrounding said impeller, an annulus in said impeller housing surrounding said impeller blades, a cone diffuser passage in said housing, and a logarithmic spiral section in said annulus and extending over less than a 90° arc of said annulus to connect said annulus to said diffuser passage.
3. In a centrifugal pump, the combination of an impeller, said impeller comprising a hub and a set of impeller blades, an impeller housing surrounding said impeller, an annulus in said impeller housing surrounding said impeller blades, a removable member having a double cone diffuser passage in said housing, said diffuser passage being composed of a first cone portion having an optimum diffuser cone angle and a second cone portion having a steeper diffuser cone angle joining said first cone portion, and a logarithmic spiral section in said annulus to connect said annulus to said first cone portion of said diffuser passage.
4. In a centrifugal pump, the combination of a drive shaft; a main impeller rigidly secured on one end of said drive shaft; said impeller comprising a hub, a set of impeller blades mounted on said hub having the leading side rounded to a thin tip, and a rigid stiffening member secured to the one edge of said blade; an impeller housing surrounding said impeller having an aperture therein for rotatable mounting of said drive shaft; a fluid inlet passage through said impeller housing to said impeller blades; an annulus having a semi-circular cross section in said impeller housing surrounding said impeller blades; a removable member having a double cone diffuser passage therein, said removable member mounted in an aperture in said housing, said diffuser passage being composed of a first cone portion having an optimum diffuser cone angle and a second cone portion having a steeper diffuser angle; a logarithmic spiral section in said annulus to connect said annulus to said first cone portion of said diffuser passage, a dynamic seal between said drive shaft and said housing comprising a small centrifugal impeller shrouded on one side and rigidly mounted on said shaft in a hollow in said housing, said shrouded side facing said impeller, and a passage from the shrouded side of said small impeller through a portion of the housing to the impeller; and a restriction between the drive shaft and the housing to restrict fluid flow.

5. In a centrifugal pump, the combination of a drive shaft; an impeller rigidly secured on one end of said drive shaft; said impeller comprising a hub, a set of impeller blades mounted on said hub having the leading side rounded to a thin tip, and a rigid stiffening member secured to the one edge of each said blade; an impeller housing surrounding said impeller having an aperture through one side thereof for rotatable mounting of said drive shaft; a fluid inlet passage to said impeller blades through a side opposite said one side of said impeller housing; a circular recess in said one side of said impeller, said stiffening member rotating in said circular recess; an annulus having a semi-circular cross section in said impeller housing surrounding said impeller blades, a removable member having a double cone diffuser passage therein mounted in an aperture in said housing, said diffuser passage being composed of a first cone portion having an optimum diffuser cone angle and a second cone portion having a steeper diffuser cone angle; and a logarithmic spiral section in said annulus to connect said annulus to said first cone portion of said diffuser passage.

6. In a centrifugal pump, the combination of an impeller comprising a hub having a center line; and a set of radially extending impeller blades mounted on said hub and having tips defining a substantially cylindrical surface on the rotation thereof concentric with the aforesaid center line, an impeller housing surrounding said impeller, said housing having an annulus of semi-circular cross section surrounding said impeller with the open diametral side of said annulus forming a substantially cylindrical plane parallel with said center line facing said blades, the cylindrical surface defined by said blade tips and the cylindrical surface defined by the open diametral side of said annulus lying in a common plane, said semi-circular cross section of said annulus having a constant cross section over an arc of approximately 270 degrees.
